UNITED STATES PATENT OFFICE.

GEORGE B. SMITH, OF CHICAGO, ILLINOIS, ASSIGNOR TO J. M. KELLY, TRUSTEE, OF PITTSBURG, PENNSYLVANIA.

DESIGN FOR A BADGE.

SPECIFICATION forming part of Design No. 22,259, dated March 7, 1893.

Application filed November 17, 1892. Serial No. 452,345. Term of patent 14 years.

To all whom it may concern:

Be it known that I, GEORGE B. SMITH, of Chicago, in the county of Cook and State of Illinois, have invented a new and original 5 Design for Badges, of which the following is a full, clear, and exact description, reference being had to the accompanying drawing, forming part of this specification, which shows in plan view a badge embodying my design.

10 My design consists in a badge having the configuration substantially as hereinafter described and as stated in the claim.

The essential features of my design are the representation of a belt, a horse-shoe, and an 15 initial letter, substantially as shown in the drawing.

In the drawing, a is the representation of the belt, arranged in the form of a circle, and having the representation of a buckle b. Inside of the belt a is the representation of a 20 horse-shoe c, and d is the representation of the initial letter.

I claim—

The design for a badge consisting in the representation of a belt, a horse shoe, and the 25 initial letter, substantially as shown and described.

In testimony whereof I have hereunto set my hand this 4th day of November, A. D. 1892.

GEORGE B. SMITH.
